UNITED STATES PATENT OFFICE.

CHARLES W. WARNER, OF MIDDLETOWN, CONNECTICUT, ASSIGNOR TO GOOD MANUFACTURING COMPANY, OF NEW YORK, N. Y., A CORPORATION OF INDIANA.

DESIGN FOR A SHELF-BRACKET.

43,446.

Specification for Design.

Patented Jan. 7, 1913.

Application filed September 26, 1912. Serial No. 722,533. Term of patent 7 years.

To all whom it may concern:

Be it known that I, CHARLES W. WARNER, a citizen of the United States, residing at Middletown, in the county of Middlesex and State of Connecticut, have invented a new, original, and ornamental Design for a Shelf-Bracket, of which the following is a specification, reference being had to the accompanying drawing, forming part thereof.

Figure 1 is a view looking down from the front of a shelf bracket of my new design. Fig. 2 is a side view of the bracket.

I claim:

The ornamental design for a shelf bracket as shown.

CHARLES W. WARNER.

Witnesses:

A. A. HURD,
E. M. DOOLEY.
